UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A CHILD'S COAT.

SPECIFICATION forming part of Design No. 17,825, dated October 25, 1887.

Application filed August 8, 1887. Serial No. 246,460. Term of patent 3½ years.

To all whom it may concern:

Be it known that I, ETTA L. JENKINS, of the city, county, and State of New York, have invented and produced a new and original 5 Design for a Pattern of a Child's Coat; and I do hereby declare that the engraved prints accompanying this specification convey to any one accustomed to using paper patterns a clear understanding of how a garment made 10 up by the pattern will appear.

The design shows a full skirt depending from a round waist, the skirt exhibiting a box-plait just back of each front edge and gathers at the top, and displaying the front edges separating 15 slightly. The waist displays a box-plait on

each front and on each side of the back, the lower parts of the trimming of the waist box-plaits falling in looped lapels on the skirt, front and back. The waist-front displays buttons down the center, a deep round collar, and 20 coat-sleeves.

What I claim as my invention, and desire to secure by Letters Patent, is—

The design for a child's coat, as shown in the engraved print accompanying this specification. 25

ETTA L. JENKINS.
